GAS ILLUMINATED SLIDE PROJECTOR

Luther A. Blackburn, Eagle Rock, Calif.

Application March 31, 1959, Serial No. 55,275

Term of patent 14 years

(Cl. D61—1

Fig. 1 is a side elevational view of a gas illuminated slide projector, showing my new design, the opposite side being substantially a mirror image thereof;

Fig. 2 is a top plan view;

Fig. 3 is a front elevational view; and

Fig. 4 is a rear elevational view thereof.

The broken line showing of a representative gas fueled illuminator is for illustrative purposes only.

I claim:

The ornamental design for a gas illuminated slide projector, substantially as shown and described.
